By his Attorneys,

John P. Mohler, Inventor

C. A. Snow & Co.

UNITED STATES PATENT OFFICE.

JOHN PETER MOHLER, OF BURLINGHAM, OHIO.

DESIGN FOR A FENCE-POST.

SPECIFICATION forming part of Design No. 28,474, dated April 12, 1898.

Application filed March 5, 1898. Serial No. 672,784. Term of patent 7 years.

To all whom it may concern:

Be it known that I, JOHN PETER MOHLER, a citizen of the United States, residing at Burlingham, in the county of Meigs and State of Ohio, have invented a new and original Design for a Fence-Post, of which the following is a specification.

This invention relates to a new and original design for a fence-post; and it has for its object to provide a design of this character that shall be both useful and ornamental.

The leading feature of the design resides in an elongated cylindrical body provided with a series of exterior-spaced annular grooves and a series of spaced rectangular openings 15 piercing the body at right angles to its length.

The minor features of the design are the body being provided with spaced pairs of annular angular ribs, each pair of said ribs having a V-shaped annular groove therebetween, and in the rectangular openings being located within the plane of said grooves so as to intersect the latter.

In the drawings, Figure 1 is an elevation of 25 a fence-post embodying the herein-described design. Fig. 2 is a vertical longitudinal sectional view thereof.

Referring to the accompanying drawings, the numeral 1 represents an elongated tubular cylindrical body provided at regularly-spaced points with the spaced pairs of annular angular ribs 2, which by reason of their angular shape produce therebetween the annular V-shaped grooves 3, each pair of said ribs 2 having a groove 3 between the same. In addition to the annular ribs and grooves the cylindrical body 1 of the fence-post is further provided with a series of spaced rectangular openings 4, which lie within the planes of the grooves 3 and intersect the latter, as clearly illustrated in the drawings.

To complete the design, the fence-post body is provided at its lower end with an enlarged circular base-collar 5.

What I claim is—

The design for a fence-post herein shown and described.

In testimony that I claim the foregoing as my own I have hereto affixed my signature in the presence of two witnesses.

JOHN PETER MOHLER.
